CURTAIN FIXTURE

Charles A. Plaunt, Maywood, Ill.

Application November 28, 1936, Serial No. 113,218

2 Claims. (Cl. 248—263)

This invention relates to curtain fixtures of that type designed for supporting both curtains and drapes.

It is an object of the invention to provide a fixture which can be attached securely to the top of a window frame at any point without necessitating the use of screws, nails or the like and without scarring the exposed surfaces of the frame.

10 A further object is to provide a fixture which can be quickly placed in or removed from position without requiring any particular skill.

A still further object is to provide a fixture the bracket portion of which can be adjusted to any 15 desired elevation relative to the base portion of the fixture, the entire structure being easy to manufacture and salable at low cost.

With the foregoing and other objects in view which will appear as the description proceeds, the 20 invention consists of certain novel details of construction and combinations of parts herein-after more fully described and pointed out in the claims, it being understood that changes may be made in the construction and arrangement of 25 parts without departing from the spirit of the invention as claimed.

In the accompanying drawing the preferred form of the invention has been shown.

In said drawing:

30 Figure 1 is a front elevation of a portion of a window frame showing a pair of fixtures applied thereto, these fixtures being constructed in accordance with the present invention.

Figure 2 is a plan view of the structure shown 35 in Figure 1.

Figure 3 is a section on line 3—3, Figure 1.

Figure 4 is a section on line 4—4, Figure 1.

Figure 5 is a perspective view of a gripping plate.

40 Figure 6 is a perspective view of the plate carrying lever.

Figure 7 is an elevation of the adjustable rod used in connection with the fixtures.

Referring to the figures by characters of reference 45 1 designates the base plate of the fixture the upper end of which is bent backwardly at right angles to form a gripping and supporting head 2 while extending laterally from the lower end of the base is a short arm 3. Stiffening flanges 4 extend along the side edges of the base 1 and the corresponding edges of the head 2 and these flanges cooperate with the base to form a channel into which are extended upwardly projecting angular hooks 5 struck from the base 50 1 and arranged in a longitudinal series,

Pivottally connected to the arm 3 is a lever 6 the free end of which has an ear 7 projecting upwardly therefrom and formed with an aperture 8 and a slot 9. A wing 10 is pivotally attached to the lever 6 close to ear 7 and is extended upwardly from one side of a gripping plate 11. This gripping plate, as well as the head 2, is formed with small spurs or teeth 12.

A coiled spring 13 is attached at one end to the upper portion of base 1 at one side thereof while its other end is secured in either the opening 8 or the slot 9, the point of attachment depending upon the tension desired in the spring.

The bracket portion of the fixture comprises a flat strip of metal bent into U-shape to provide 15 a long arm 14, a short arm 15, and an intermediate or base portion 16. Each arm has a slot 17 extending downwardly thereinto at a point adjacent to its free end and the fixture is so proportioned as to fit snugly between the flanges 4 and against the base 1. An angular aperture 18 20 is provided in the base portion 16 of the bracket and is of an area slightly greater than that of any of the hooks 5. Thus by inserting the base portion of the bracket between the flanges, the aperture 18 can be caused to receive one of the hooks 5 after which, by sliding the bracket downwardly, the upper portion thereof will engage in one hook while the lower portion will engage in the hook therebelow. Thus the bracket will be securely held to the base as shown.

In practice it is intended to use a pair of these fixtures, one being a "right" and the other being a "left." The fixture to be mounted on the window frame F is placed with its base 1 against the face of the frame and with its head 2 overlying the frame. Lever 6 is swung downwardly so as to place the spring 13 under increased tension and to increase the distance between gripping plate 11 and head 2. Thus it is possible for the plate 11 to extend under the top of the window frame while the head 2 is resting on said top. When the spring 13 is released it will pull on ear 7 and cause plate 11 to thrust upwardly against the under surface of the top of the frame, the prongs or spurs 12 biting against the surface of the frame and said plate adjusting itself to proper position for engagement with the frame. Obviously the fixture thus will be clamped firmly on the frame no matter in what position it might be placed along the top thereof and after it has been located in proper position the bracket can be mounted on the base as shown. When the fixtures are properly located, the short arms 15 of the brackets will be located between the 55

long arms thereof. These short arms thus can be used for supporting a rod on which curtains are to be mounted while the long arms 14 can be used for supporting a rod on which drapes 5 can be mounted. As shown in Figure 7 the rod can be made extensible. It is preferred to form it of an elongated flat strip 19 having opposed transverse slots 20 near one end. This strip is 10 slidable on another strip 21 provided with in-turned longitudinal flanges 22 which lap strip 19. Opposed transverse slots 23 are provided in the strip 21 near its outer or free end.

To mount one of these extensible portions on the brackets, the strips 19 and 21 are slid relative to each other so as to bring the slots 20 and 15 23 a distance apart equal to the distance between those arms 14 or 15 to be engaged. Slotted portions of the strips 19 and 21 are then inserted downwardly within the slots 17 so that the members 19 and 21 will become interlocked with the 20 arms 14 or 15 and the fixture is then ready for use.

What is claimed is:

1. A curtain fixture including a base having an offset head at one end and a longitudinal series 25 of out struck hooks, a bracket having an aperture for receiving one of the hooks, said bracket being

slidable on the received hook into engagement with an adjoining hook of the series, stiffening flanges on the base for holding the bracket centered on the hooks, a lever fulcrumed on the base, a resilient connection between the lever and the 5 base, and a gripping plate pivotally connected to and extending laterally from the lever.

2. A curtain fixture including a base having an offset head at one end, a lever pivotally connected to the other end of the base and extending laterally therefrom, resilient means for urging the lever about its pivotal connection and toward the head, a gripping plate pivotally connected to the lever and extending laterally therefrom, said plate and head being positioned to receive the top portion of a window frame therebetween, and a bracket detachably connected to the base, said bracket including spaced arms of different lengths and an apertured intermediate portion, there being a longitudinal series of hooks 20 outstanding from the base, each hook being proportioned to enter the aperture in the bracket and said bracket being adapted to gravitate on the engaged hook and into engagement with the next adjoining hook thereunder. 25
